UNITED STATES PATENT OFFICE.

FREDERICK W. MARTIN, OF NEW YORK, N. Y., ASSIGNOR TO FRANKLIN RAILWAY SUPPLY COMPANY, OF WILMINGTON, DELAWARE, A CORPORATION OF DELAWARE.

LOCOMOTIVE DRIFTING-VALVE DEVICE.

1,163,100.

Specification of Letters Patent. Patented Dec. 7, 1915.

Application filed April 23, 1915. Serial No. 23,363.

To all whom it may concern:

Be it known that I, FREDERICK W. MARTIN, a citizen of the United States, residing at the borough of Manhattan, in the city, county, and State of New York, have invented a certain new and useful Improvement in Locomotive Drifting-Valve Devices, of which improvement the following is a specification.

10 This invention relates to drifting valve connections for locomotives, in which the drifting valve operates to supply a small amount of saturated steam to the engine cylinders when the engine is running with the throttle closed, for the purpose of preventing the formation of a vacuum by the movement of the pistons and for furnishing sufficient lubrication. With some forms of drifting valves it is possible that a small 15 amount of steam might be admitted to the engine cylinders when the locomotive is standing still, which might cause an accidental and undesired starting of the locomotive, and one of the objects of my present invention is to provide means whereby any steam admitted through the drifting valve at such times may pass to both sides of the piston and have no tendency to start the locomotive.

30 Another object is to provide improved means for lubricating the engine by the steam admitted through the drifting valve. Another feature comprises improved means operated by live steam pressure from the 35 throttle for closing the admission of steam through the drifting valve, so that when the throttle is open for driving the engine with superheated steam the admission of saturated steam from the drifting valve will be 40 prevented.

According to one feature of my improvement, steam from the drifting valve is introduced into both ends of the engine cylinders, on opposite sides of the pistons, so 45 that there will be no tendency to move the same, and as the discharge ports from one end of the cylinder will be open to the exhaust nozzle, the steam will blow out

through the nozzle, and up through the stack, thereby acting as a blower.

50 In the accompanying drawing: Figure 1 is a side elevation showing the manner of connecting the drifting valve devices to the engine cylinder, the valve chest and cylinder being partially shown in section with the lower part of the cylinder broken away; Fig. 2, a vertical section of the improved drifting check valve device; and Fig. 3, a similar view taken at right angles to Fig. 2.

55 Any suitable form of drifting valve, 5, may be employed for controlling the admission of a small amount of steam when the locomotive is running with the throttle closed, such as shown for instance in the prior Patent No. 1,080,290, dated December 2, 1913. The steam from the drifting valve, 6, may be admitted into the engine cylinders either directly or through the valve chest, 7, and according to my present improvement, 60 in order to prevent a pressure from accumulating at one side of the engine piston when the same is standing still, I provide a by-pass connection, such as pipes, 8, 8, communicating with the main steam ports, 9, 9, at opposite ends of the cylinder, 10, whereby 65 the steam may have access to both sides of the piston. For the purpose of closing communication to or through the by-pass connection when the engine is running with 70 the throttle open, a valve means operated by the live steam pressure from the valve chest, or 75 communicating supply conduit, is employed.

80 According to the preferred construction shown in the drawing, this valve device comprises a casing, 7, connected to the by-pass pipes, 8, 8, and to the pipe, 6, leading from the drifting valve, 5, and containing the differential piston valve, 11, having a 85 groove, 12, for establishing communication through the by-pass, and a valve head, 13, for controlling the admission of steam from 90 the drifting valve pipe, 6, to passage, 14, and pipe, 15, leading into the outside live steam supply pipe, 16, communicating directly with the valve chest, 17, containing 95 the engine distribution valve, 18. The

chamber, 19, of the large head of the differential piston, 11, communicates at its lower end by a port, 20, with the live steam supply from the throttle through pipe, 15, so that when the engine is running with throttle open, this pressure holds the piston valve seated in its upper position with the inlet from the drifting valve and the communication through the by-pass closed.

10 When the engine is running and the throttle is closed, that is, when the engine begins drifting, the drifting valve, 5, is opened in any suitable manner, and a small amount of saturated steam from the boiler is admitted to the pipe, 6, and the small valve head, 13, of the differential piston, 11. As the pressure in chamber, 19, beneath the large head of the piston, 11, is at this moment greatly reduced on account of the throttle being closed, the pressure acting on valve, 13, is sufficient to move the differential piston valve, 11, downward, thereby admitting steam through passage, 14, and pipes, 15 and 16, into the valve chest. It is then supplied to both ends of the engine cylinder by means of the distribution valve, in the usual way, thereby preventing the formation of a vacuum by the movement of the piston, and also affording a means of lubrication for the cylinder. When the locomotive comes to a stop, or at any time when standing still, if the drifting valve, 5, should for any reason be open, the steam which is admitted to the valve chest will first pass to one end or the other of the cylinder, according to the position of the distribution valve, and then flow through the open by-pass to the other end of the cylinder, which may also be open by the distribution valve to the exhaust. In this way steam is admitted to both sides of the engine piston so that no pressure can accumulate on either side sufficient to cause an accidental starting of the locomotive, which is undesired, and might at times be dangerous. As soon as the throttle is opened at any time, the differential piston valve promptly closes, thereby cutting off the admission of steam from the drifting valve and closing communication through the by-pass. By this means saturated steam from the drifting valves is prevented from mingling with the superheated steam used for running the engine when throttle is open, and the by-pass does not in any way interfere with the normal operation.

When the locomotive is standing, it is evident that at least one of the cylinders will be open through its distribution valve to the exhaust nozzle, and as the pipe, 6, from the drifting valve is branched at 6^a, to supply similar devices on both cylinders, it will be apparent that the steam admitted

by the drifting valve will blow out through the exhaust nozzle and stack, and thereby 65 act as a blower. In this way the apparatus may be used at station stops for the purpose of lifting the smoke and make it unnecessary for the blower valve to be open.

Another feature of my improvement comprises the connection of the oil pipe, 21, to the passage between the check valve, 18, and the valve chest, whereby when the engine is drifting, the steam passing through the check valve will take up and atomize this 75 oil, and carry it to all parts of the valve chest and cylinder so as to insure a thorough lubrication during the drifting period.

Having now described my invention, what I claim as new and desire to secure by Letters Patent is:

1. In a locomotive drifting valve mechanism, the combination of a drifting valve for controlling the admission of a limited amount of steam to the engine cylinders 85 when the throttle is closed, a by-pass between the opposite ends of the cylinders, and a valve device governed by pressure admitted through the throttle for controlling said by-pass and the supply of steam from 90 the drifting valve.

2. In a locomotive drifting valve mechanism, the combination of a drifting valve for controlling the admission of a limited amount of steam to the engine cylinders 95 when the throttle is closed, a by-pass between the opposite ends of the cylinders, and a differential piston valve subject to the pressures admitted through the throttle, and through the drifting valve for controlling 100 said by-pass.

3. In a locomotive drifting valve mechanism, the combination of a drifting valve for controlling the admission of a limited amount of steam to the engine cylinders 105 when the throttle is closed, and a differential piston valve operated by pressure admitted through the throttle for closing communication from the drifting valve to the cylinders.

4. In a locomotive drifting valve mechanism, the combination of a drifting valve for controlling the admission of a limited amount of steam to the engine cylinders 111 when the throttle is closed, a by-pass between the opposite ends of the cylinders, and a valve device operated by pressure admitted through the throttle for closing the supply from the drifting valve and closing communication through said by-pass.

5. In a locomotive drifting valve mechanism, the combination of a drifting valve communicating with the engine valve chest and controlling the admission of a limited amount of steam, the engine cylinder having a by-pass between its opposite ends, and

a valve device subject to the opposing pressures from the drifting valve and from the throttle for controlling said by-pass.

6. In a locomotive drifting valve mechanism, the combination of a drifting valve having a communication leading to the engine valve chest and controlling the admission of a limited amount of steam, a valve device operated by pressure admitted

through the throttle for closing communication from the drifting valve to the valve chest, and an oil supply pipe connected to said communication between said valve device and engine valve chest.
